UNITED STATES PATENT OFFICE.

EDWARD L. BUCKINGHAM, OF BROOKINGS, SOUTH DAKOTA, ASSIGNOR
OF ONE-HALF TO JESSE M. KEITH AND H. D. HALL, OF DES MOINES,
IOWA.

THILL-SUPPORT.

SPECIFICATION forming part of Letters Patent No. 755,997, dated March 29, 1904.

Application filed December 7, 1903. Serial No. 184,001. (No model.)

To all whom it may concern:

Be it known that I, EDWARD L. BUCKINGHAM, a citizen of the United States of America, and a resident of Brookings, Brookings county, 5 South Dakota, have invented a new and useful Thill-Support, of which the following is a specification.

The object of this invention is to provide improved means for supporting thills independent of and auxiliary to means employed to attach said thills to an axle.

My invention consists in the construction, arrangement, and combination of elements hereinafter set forth, pointed out in my claims, 15 and illustrated by the accompanying drawings, in which—

Figure 1 is a view transversely of an axle, showing my device applied in such manner as to sustain a thill in its uppermost position. 20 Fig. 2 is a view similar to Fig. 1, showing my device applied to a thill in its normal position. Fig. 3 is a detail view of a thill-clip and several parts attachable thereto. Fig. 4 is a view of an axle-clip, partly in section. Fig. 5 is a 25 front elevation of the axle-clip shown in Fig. 4, said clip positioned as required for practical use.

This invention relates to and is an improvement on Letters Patent of the United States 30 No. 560,967, granted to me on the 26th day of May, 1896.

In the construction of the device as shown the numeral 10 designates an axle, 11 a thill, and 12 13 members of a thill-coupling where- 35 by the thill is hinged or pivoted to and sup- ported by the axle. A supporting-clip 14 is provided and formed with a base extending beneath the axle 10 and provided with fork- arms 15 16 on its forward end. The base of 40 the clip 14 is curved or otherwise shaped to conform to the lower surface of the axle 10, and a lug or shoulder 17 on each of the fork- arms 15 16 extends upward in front of and in 45 contact with said axle. The base of the clip 14 also extends upward at the rear of and in contact with the axle 10, and an arm 18 is formed on and extends from the uppermost portion of said base. The arm 18 is relatively thin and preferably is ductile or malleable in

order that it may be bent over and caused to 50 embrace the axle 10 or an axle-bar or cap-piece 19, mounted thereon. The arm 18 terminates in a threaded bolt 20, integral therewith, and the threaded portion of said arm may be carried between the fork-arms 15 16 of the base 55 and secured therein by means of a nut screwed thereon. When the threaded portion 20 of the arm 18 is confined between the fork-arms 15 16 of the base by the nut 21, as shown in Figs. 1, 2, and 5, the clip 14 thereby is rigidly 60 mounted on the axle 10. Since various sizes of axles and axle-bars are employed in various styles of vehicles and implements, it will be desirable to make the supporting-clips 65 14 in various sizes in order that each clip 5 may fit snugly and bind upon one or another form, size, or character of axle, and when so mounted be immovable torsionally of said axle. An arm 22 is formed on and extends rearwardly from the base of the supporting- 70 clip 14, and said arm is formed with a curved aperture 23 in its extremity, Fig. 4. A thill-clip is provided and formed of a base 24, ar- ranged for contact with one side of the thill 11. A strap or arm 25 is formed integral 75 with the base 24 and preferably is ductile or malleable in order that it may be bent around and caused to embrace the thill. The strap or arm 25 terminates in a fork 26 and is formed with a shoulder 27, designed to contact with 80 the base 24 when the device is folded and mounted as shown in Figs. 1 and 2. A thread- 85 ed bolt or stud 28 is formed on and extends downward from the base 24 of the thill-clip and is arranged to be embraced by the fork 26 at times, said fork held in position on said bolt or stud by a nut 29, removable and replaceable thereon. A threaded bolt or stud 30 is formed on and projects laterally from the base 24 of the thill-clip, preferably at 90 right angles to the stud or bolt 28, and a slide- bearing 31 is mounted thereon and confined by a nut 32 and washer 33. The slide-bear- 95 ing 31 has a horizontal aperture to receive the threaded stud or bolt 30 and also has an aper- ture 34 at right angles to the first for a pur- pose about to be made plain. A supporting- rod 35 is provided and is formed with a coil

or coils 36 in one end portion and a hook 37, projecting from said coil or coils. The supporting-rod 35 preferably is made of spring-steel, and the hook 37 thereof is mounted re-
5 movably and replaceably in the curved aperture 23 of the arm 22 of the supporting-clip 14. The rod 35 extends through the aperture or slide-seat 34 in the bearing 31, and a collar 38 is mounted on and fixed by means of a set-
10 screw 39 to the rod. The outer end portion of the rod 35 is threaded, and a nut 40 is mounted thereon. It will be observed that the bearing 31 is between the collar 38 and nut 40 on the rod 35.
15 In practical use, the parts mounted as shown in Figs. 1 and 2, the supporting-rod 35 tends by reason of the resilience of its coil or coils 36 to lift the thill 11 through engagement of the slide-bearing 31. It is desirable to make the
20 rod 35 of such length that when the thill is on the ground the nut 40 on the extremity of said rod will engage the bearing 31. When the harness of the draft-animal is detached from the thill 11, said thill may be raised manually into
25 the position shown in Fig. 1. The labor of lifting the thill is assisted by the resilience of the rod 35. The thill 11 may be raised to the extent permitted by the collar 38, and said collar may be adjusted longitudinally of the rod 35 to the
30 desired degree and locked thereto by the set-screw 39. The collar 38 is employed to prevent the thill rising with such force and to such degree as to damage the dash of the vehicle to which the thill is attached. It is de-
35 sirable to make the rod 35 of such resilience that it will sustain the thill 11 when said thill is placed in the elevated position. (Shown in Fig. 1.) It may be found desirable in some classes of work to make the rod 35 of such
40 resilience as to lift the thills independently of any manual operation whenever said thills are detached from the harness of the draft-animal. Such construction is indicated when the thill-support is employed in conjunction with
45 a horse-detaching mechanism, in which event the thills would rise when the horse is de-

tached and prevent contact thereof with the ground, at the same time bringing the thills into position for manual operation to guide the vehicle.

50

I claim as my invention—

1. In a thill-support, a supporting-clip comprising a base, an arm or strap integral with said base and arranged to embrace an axle, an arm on said base, a resilient rod mounted on 55 said latter arm, a thill-clip embracing said rod and means for limiting the movement of the thill-clip relative to said rod.

2. In a thill-support, an axle-clip, a thill-clip, a slide-bearing pivoted on the thill-clip, 60 and a resilient rod mounted on the axle-clip and extending through said slide-bearing.

3. In a thill-support, an axle-clip, a thill-clip, a slide-bearing pivoted on the thill-clip, and a resilient rod formed with a hook engag- 65 ing the axle-clip, a coil or coils adjacent said hook and a body portion extending through said slide-bearing, together with means for adjusting the movement of the slide-bearing relative to said rod.

4. In a thill-support, a thill-clip, comprising a base, threaded studs on said base, a strap on said base arranged for engagement with one of said threaded studs, means for attaching said strap to said stud, a bearing on the other 75 of said studs and a rod connected to an axle and extending through said bearing.

5. In a thill-support, an axle-clip, a strap on said axle-clip, a fork on said axle-clip, and means for fixing one end of said strap in said 80 fork.

6. In a thill-support, a thill-clip, a stud on said thill-clip, a forked strap on said clip, embracing said stud, means for fixing said forked strap to said stud, and a bearing mounted on 85 said clip.

Signed by me at Brookings, South Dakota, this 5th day of October, 1903.

EDWARD L. BUCKINGHAM.
